UNITED STATES PATENT OFFICE

2,529,221

COVER FOR SEPARATOR FRAMES

Hans Olof Lindgren, Smedslatten, Sweden, assignor to Aktiebolaget Separator, Stockholm, Sweden, a corporation of Sweden

Application June 19, 1945, Serial No. 600,381
In Sweden July 7, 1944

6 Claims. (Cl. 233—21)

1

The bowl of centrifugal separators is usually enclosed in a chamber arranged in the frame of the machine, this chamber being closed by a cover, which is also used as a receiving vessel for separated material and for this purpose provided with suitable receiving chambers. Heretofore, the receiving chambers were constructed either with a bottom, i. e., downwardly closed, or without a bottom, i. e., downwardly open. In the latter case, in their closed position, they were continued and shut by channels arranged in the frame. The cover had then to be provided with tightening surfaces, and usually also packings, contacting with the frame, so as to prevent communication between the receiving chambers. With constructions of this type there is, however, always a risk of leaking owing to untight packings and the like. The inconvenience of this is apparent when taking into account that, for instance in purifying oils by removing water therefrom, the separated liquids may become remixed if there is a leakage. The inconvenience is only enhanced by the fact that it is impossible to know to what extent leaking has really taken place. It is true that with the downwardly closed receiving chambers these inconveniences are avoided, but in that case there are difficulties with the cleaning of the chambers which, in addition, cannot be made sufficiently deep.

By the present invention, which relates to a cover for separator frames developed to a receiving vessel, all the inconveniences referred to are avoided by providing the cover with an upper and/or outer receiving chamber, having a bottom, for separated lighter material and a lower and/or inner downwardly open receiving chamber for separated heavier material, which latter chamber, when the cover is placed on the frame, is completed and closed downwardly by the frame, but becomes accessible to inspection, cleaning, etc. when it is lifted off or tilted up, the tightening surface or surfaces of the cover with the frame being so positioned that, when the cover is lifted off or tilted up, the separator bowl becomes free and can readily be lifted out of the frame. It is true that the upper and/or outer receiving chamber does not thereby become accessible for cleaning at the same time as the lower and/or inner receiving chamber, but it will be understood that the most important is that the latter receiving chamber, which generally receives the impure liquid component, first and foremost becomes accessible for cleaning, and that uncontrollable leaking of the liquid is prevented, particularly leakage of the impure component into the purified component.

2

The cover should thereby be so constructed that the lower and/or inner receiving chamber is limited by two co-axial conical walls, the one of which preferably being elastically connected to the other, and further so that the upper part of the upper and/or outer receiving chamber is closed by a removable part. The lower and/or inner conical wall should be provided with a surface making a tight joint with the frame, and the bottom of the upper and/or outer receiving chamber should also be constructed with a surface making a tight joint with the frame. If, as is often the case, the cover is tilttable on hinges, it is desirable to locate the tightening surface of the lower and/or inner conical wall in another plane, preferably a higher plane, than the tightening surface in the bottom of the upper and/or outer receiving chamber.

The accompanying drawing shows by way of example one embodiment of the invention. The separator frame F has a wall 1 defining a chamber 1^a for receiving the centrifugal bowl 2, the top of the frame being closed by a movable cover 3. At its upper portion the frame extends outwardly from the wall 1 and has a wall 1^b forming therewith an upwardly opening channel 7 which preferably extends completely around the bowl receiving chamber 1^a. Below the top of the frame F, the latter is provided with an outlet 7^a leading from the channel 7 for discharging one of the separated constituents, in this instance the heavier constituent. In the cover 3 there are two receiving chambers, one upper and/or outer 4, provided with a bottom 5, and one lower and/or inner 6, open downwardly, and continued and closed by the channel 7 in the frame. The chamber 6 for the separated heavier constituent is limited by two co-axial conically shaped walls 8, 9, the latter of which is connected to the former by an elastic device 10. The lower and/or inner conical wall 9 is provided with a tightening surface 11 contacting with the frame, and the bottom 5 is likewise provided with a surface 12 making a tight joint with the frame, the latter surface being provided with a packing. This tightening surface may of course also be so constructed as to make it possible to dispense with the packing, and on the other hand it would also be possible to provide the tightening surface 11 with a packing. The cover 3 is tilttable around a shaft 13 and for this purpose journaled on the shaft by means of an arm 14 which extends from a detachable part 15, by screws fixed to and closing the upper and/or outer receiving chamber of the cover.

With the new construction it is possible, after unscrewing the screws and tilting up only the detachable part 15, to clean the receiving chamber 4 for the lighter separated constituent, and also to arrange the cover so as to permit tilting in several directions relative to the frame by turning the detachable part and correspondingly fixing the hinge member 17 to the frame. The receiving chamber 4 communicates by a tube 16, forming part of the cover, with an outlet 18 which forms part of the frame F and is disposed outwardly of channel 7. A tight joint is preferably obtained between the tube 16 and the pipe line by means of a packing, the thickness of which may be varied in any suitable manner, as by using rings of different thickness, etc., so that a satisfactory tight joint is obtained at the same time as at other tightening surfaces.

The above arrangement has only been described by way of example and its details may therefore be varied in one or more respects. Additional receiving vessels may e. g. be arranged on top of those illustrated, and especially a receiving vessel for surplus liquid may be provided.

I claim:

1. A centrifugal separator comprising a frame having a wall at least partly defining a bowl-receiving chamber, the frame also having a wall disposed outwardly from said first wall and forming therewith an upwardly opening channel surrounding said chamber, the frame also having below its top an outlet from said channel for a separated heavier constituent, and a movable cover for the frame having an annular receiving chamber for a separated lighter constituent, the cover also having a second annular receiving chamber for said heavier constituent and opening downwardly into said channel in the frame, said downward opening extending continuously around said first wall of the frame, the cover including an annular inner wall normally resting upon said first wall of the frame and forming an upward extension of the inner wall of said channel.

2. A centrifugal separator according to claim 1, in which said cover includes a top releasably connected to the underlying part of the cover and partly defining said receiving chamber for the separated lighter liquid, and a pivotal connection between said top and the frame and on which the cover is adapted to swing on a horizontal axis.

3. A centrifugal separator according to claim 1, in which the bottom of said lighter constituent receiving chamber is closed and has a surface making a tight joint with said outer frame wall

of said channel around the periphery of the channel.

4. A centrifugal separator comprising a frame having a wall at least partly defining a bowl-receiving chamber, the frame also having a wall disposed outwardly from said first wall and forming therewith an upwardly opening channel extending along the periphery of the chamber, the frame having below its top an outlet from said channel for a separated heavier constituent and also having below its top an outlet for a separated lighter constituent, said last outlet being separated from the channel by said outer wall of the frame, a movable cover for the frame having an annular receiving chamber for said separated lighter constituent and also having a second annular receiving chamber for said separated heavier constituent, said last receiving chamber opening downwardly into said channel in the frame and having an inner annular wall resting upon said first wall of the frame, said lighter constituent receiving chamber having a bottom resting upon said outer wall of the frame and closed except for a discharge passage leading downward into said frame outlet for the separated lighter constituent, and a packing extending along the outer periphery of the channel between said bottom and said outer wall of the frame, said packing having its outer edge bordering upon atmosphere, whereby leakage of one separated constituent into the other is prevented.

5. A centrifugal separator according to claim 4, comprising also a packing surrounding said passage and disposed between the cover and the frame, said packings being separated by atmosphere.

6. A centrifugal separator according to claim 4, comprising also a packing between said first wall of the frame and said inner annular wall of the heavier constituent receiving chamber, said last packing having its inner edge bordering upon said bowl-receiving chamber.

HANS OLOF LINDGREN.
